Primary Examiner — Daniel D Bui*(74) Attorney, Agent, or Firm* — Weber Rosselli & Cannon LLP(57) **CLAIM**

The ornamental design for a solar cell, as shown and described.

DESCRIPTION

FIG. 1 is a top perspective view of a solar cell showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a back elevation view thereof; and,

FIG. 7 is a front elevation view thereof.

In the drawing views, the dash-dot broken line and the even broken line represent unclaimed portions of the solar cell and form no part of the claimed design.

1 Claim, 3 Drawing Sheets(56)
